UNITED STATES PATENT OFFICE.

OWEN H. JONES, OF HARTFORD, CONNECTICUT, ASSIGNOR TO FLORENCE M. POMEROY,
OF HARTFORD, CONNECTICUT.

BALL-COCK

1,252,701.

Specification of Letters Patent. Patented Jan. 8, 1918.

Application filed July 28, 1917. Serial No. 183,256.

To all whom it may concern:

Be it known that I, OWEN H. JONES, a citizen of the United States, residing at Hartford, in the county of Hartford and State 5 of Connecticut, have invented a new and Improved Ball-Cock, of which the following is a specification.

My invention relates more especially to devices for supplying water to tanks used 10 for various purposes and especially those used in connection with water-closets and an object of my invention among others is to provide a ball cock that shall be simple in construction, efficient in operation and especially one that shall be free from objectionable leaking.

One form of ball cock embodying my invention and in the construction and use of which the objects herein set out, as well as 20 others, may be attained, is illustrated in the accompanying drawings, in which—

Figure 1 is a top plan view of a ball cock embodying my invention.

Fig. 2 is a view in side elevation of my improved ball cock with parts broken away in 25 central section to illustrate construction.

In the accompanying drawings the numeral 5 indicates the inlet section of my improved ball cock, this being the section to 30 which a source of supply as an inlet pipe is attached in any suitable manner, and the numeral 6 indicates the outlet section of the ball cock, that is, the section containing the chamber and from which the outlet 7 extends. A valve seat 8 of any suitable form and construction is secured to the section 5 of the ball cock, this seat being located within the chamber 9 within the outlet section of said cock. A valve plunger 10 is mounted 35 for reciprocating movement in a neck 11 constituting a part of the section 6, a valve 12 being secured to the lower end of the plunger in position to engage the valve seat 8. Ears 13 project from the end of the 40 neck 11 and a swinging block 14 is pivotally mounted between said ears, a float rod 15 being secured to said block as by means of a thumb screw 16. This float rod preferably extends into a hole in the block, this hole 45 being located between the pivot 26 support-

ing the block and the pivot 4 connecting the block and link.

This block 14 has a groove 17 in its under side, the bottom of this groove comprising a shoulder against which a link 18 abuts to 55 limit both the opening and closing movements of the valve. Said link is pivotally attached to said block and to the plunger 10 and extends within a groove in the plunger (as shown in dotted lines in Fig. 2 of the drawings) and into the groove 17. This link has a beveled or curved part 19 to permit swinging movement of the link in the opening and closing movements of the valve, the extremity 20 of the link at one end of the beveled 60 part constituting a closing stop. The edge of the link at or near the termination of the curved part at the other end thereof constitutes with the edge 21 of the groove 17 an opening stop. 70

The closing stop 20 is not effective when a new valve 12 is in place, but when said valve becomes worn to a certain extent then the closing stop 20 comes into play to determine the position of the block 14 in the 75 closing movement of the valve and thus prevents the pivot 4 from passing the "dead center" and thus allowing the float rod 15 with its float to rise, owing to its buoyancy, sufficiently to again open the valve after it 80 has been closed in the rising movement of said float. The stop formed by the curved part of the link near its lower end striking the bottom of the slot 17 determines the position 85 of the valve when it is open.

In order to prevent the passage of liquid along the plunger 10 and out at the end of the neck 11 I provide a relief groove 22 preferably of annular form in the plunger 10. This groove intercepts any liquid that would 90 have a tendency, from the pressure or otherwise, to flow along the sides of the plunger out of the chamber 9, and I also provide means for retaining any liquid that may thus flow along the sides of the plunger 95 within the body of the valve and for compelling such liquid to flow through the outlet 7. This I accomplish by providing a diaphragm 23 extending partly across the chamber within the section 6 of the valve, 100

this diaphragm forming the upper part of the chamber 9 and also forming a relief chamber 24 located within the valve body. This chamber 24 opens by a mouth 25 into the chamber 9 and from thence any liquid in the relief chamber will flow through the outlet 7. In the form of the device as shown herein the relief groove 22 is normally closed by the wall separating the relief and outlet chambers.

By this construction I effectually prevent any flow of liquid past the plunger 10 to the outside of the valve and consequently retain all of the liquid within the valve structure.

15 In accordance with the provisions of the patent statutes I have described the principles of operation of my invention, together with the device which I now consider to represent the best embodiment thereof; but I desire to have it understood that the device shown is only illustrative and that the invention can be carried out by other means.

I claim:

1. A ball cock including a body with an outlet chamber therein having an outlet therefrom, said body also having a relief chamber opening to said outlet chamber within the body, a valve plunger located within the body and closely fitting the wall between the outlet and relief chambers and having an annular groove positioned to pass into said relief chamber when the valve is open and means for operating said plunger.

2. A ball cock including a body with a chamber therein, a diaphragm extending across said chamber and dividing it into two parts constituting a relief chamber and an outlet chamber, the relief chamber opening to said outlet chamber, a valve plunger located within the body and closely fitting the opening through said diaphragm and having an annular groove positioned to pass into said relief chamber when the valve is open, and means for operating said plunger.

45 3. A ball cock including a body with an outlet chamber therein having an outlet therefrom, said body also having a relief chamber opening to said outlet chamber, said structure also having a plunger opening extending through the wall between said chambers, a valve plunger located within the body and closely fitting said opening and extending through said plunger opening, said plunger having an annular groove that is closed by the wall of said opening when the valve is in its closed position, and means for operating said plunger.

4. A ball cock including a body with a chamber therein, a diaphragm extending across the chamber dividing it into a relief and an outlet chamber, said diaphragm having an opening therethrough, a valve plunger located within the body and closely fitting said opening and extending through said

opening and having an annular groove that is closed by the edges of the opening through the diaphragm when the valve is in its closed position, and means for operating the plunger.

5. A ball cock including a body with a chamber therein, a valve seat within said chamber, a plunger located within said body and having a valve to contact with said seat, an actuating block pivotally mounted on the body, and a link pivotally connecting said block and plunger, said link extending into a groove in the block and by contact of the end of the link with the bottom of the groove forming a valve closing stop.

6. A ball cock including a body with a chamber therein, a valve seat within the chamber, a plunger located within said body and having a valve to contact with said seat, an actuating block pivotally mounted on the body, and a link pivotally connecting said block and plunger, said link extending into a groove in the block and by contact of the side of said link with the bottom of the groove forming a valve opening stop.

7. A ball cock including a body with a chamber therein, a valve seat within the chamber, a plunger located within said body and having a valve to contact with said seat, an actuating block pivotally mounted on the body, and a link pivotally connecting said block and plunger, said link extending into a groove in the block, the contact of the end of the link with the bottom of the groove forming a valve closing stop, and the contact of the side of the link with the bottom of the groove forming a valve opening stop.

8. A ball cock including a body with a chamber therein, a valve seat within the chamber, a plunger located within said body and having a valve to contact with said seat, an actuating block having a groove, said block being pivotally mounted on the body, and a link pivotally connecting said block and plunger, said link being beveled at one end and located within said groove, one end of said beveled part, by contact with the bottom of the groove, constituting a valve closing stop and the other end of said beveled part, by contact with the edge of the groove, constituting a valve opening stop.

9. A ball cock including a body having a chamber therein and an outlet therefrom, a valve plunger located within the body, a support extending from the body, an actuating block pivotally mounted on said support, a link pivotally connecting said block and plunger, a float rod secured to said block between its pivotal support and the pivotal attachment of said link and extending in a direction transverse to a line extending between said pivots.

10. A ball cock including a body with a chamber therein, a diaphragm extending

across said chamber and dividing it into two parts, a relief chamber and an outlet chamber, the relief chamber opening to said outlet chamber, and a valve plunger of substantially uniform diameter located within the body and composed of a single piece of material with an annular groove therearound positioned to be located in said relief chamber when the valve is away from its seat to prevent, when the plunger is off from its seat, flow of liquid between the plunger and the wall of the opening in the ball cock in which said plunger is located.

OWEN H. JONES.
